F. MANKEY.

MOLDING.

No. 16,653.

Patented Apr. 20, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,653, dated April 20, 1886.

Application filed November 13, 1885. Serial No. 182,755. Term of patent 7 years.

To all whom it may concern:

Be it known that I, FREDERICK MANKEY, of Williamsport, Lycoming county, Pennsylvania, have invented and produced a new and 5 original Design for Moldings, of which the following is a specification, reference being had to the accompanying photograph, forming part hereof.

My design consists in the new band shown. 10 The edges of the molding exhibit a series of scallops, A, each scallop being steeper at one side, B, than at the other side, C. On the face of the molding are diagonal channels D. I may depress the surfaces of the scallops at the 15 sides B toward the edge, so that the surfaces of the adjacent scallops at the sides C appear

in relief. Along the center line of the molding, and at equal intervals, appear annular indentations F, in which are rounded or hemispherical elevations E.

20

I claim—

The design for a molding, substantially as herein shown and described, which consists in the flat-faced band showing at opposite edges the irregular scallops A, and along the center line, at equal intervals, the annular indentations F and rounded elevations E, and channels D.

FREDERICK MANKEY.
